ISRAEL J. CURRIER AND JOSEPH HAWSE, OF WOLCOTT, VERMONT.

Letters Patent No. 92,279, dated July 6, 1869.

IMPROVED POTATO-WASHER.

The Schedule referred to in these Letters Patent and making part of the same.

To all whom it may concern:

Be it known that we, ISRAEL J. CURRIER and JOSEPH HAWSE, of Wolcott, in the county of Lamoille, and State of Vermont, have invented certain new and useful Improvements in Potato-Washers; and we do hereby declare that the following is a full, clear, and exact description thereof, reference being had to the accompanying drawings, and to the letters of reference marked thereon, which form a part of this specification, and in which—

Figure 1 represents a longitudinal section of our potato-washer, and

Figure 2, a plan view of the same.

Similar letters indicate like parts in both figures.

The nature of our invention consists in the employment of a revolving bottom and stirrer, in combination with an upright crank-shaft and bucket, said bucket being provided with parallel bars; operating substantially as hereinafter set forth.

To enable others skilled in the art to which our invention appertains, to make and use the same, we will now describe.

In the accompanying drawing—

A represents an ordinary bucket, provided at its upper end with the bar *a*, to which is attached one

end of the rods *a' a' a'*, the other end of the rods being inserted into the sides of the bucket.

B is an upright crank-shaft, passing through the bar *a*, and the lower end working in a journal secured to the bottom of the bucket.

On this shaft is secured the revolving bottom *b*, which is provided with the diagonal strips *b' b' b'*.

C is a metal S-shaped stirrer, secured on the shaft B, above the revolving bottom *b*.

Having thus described our invention,

What we claim as new, and desire to secure by Letters Patent, is—

A potato-washer, consisting of the bucket A, crank-shaft B, stirrer C, revolving bottom *b*, with diagonal strips, and cross-bars or rods *a' a' a'*, all combined, arranged, and operating substantially in the manner and for the purpose set forth.

In testimony that we claim the foregoing as our own, we affix our signatures, in presence of two witnesses.

ISRAEL J. CURRIER.
JOSEPH HAWSE.
